STOKER

Royce L. Beers, Birmingham, Mich., assignor to
Detroit Stoker Company, Monroe, Mich., a cor-
poration of Michigan

Application October 25, 1943, Serial No. 507,583

4 Claims. (Cl. 110—47)

The invention relates to stokers of that type in which the fuel is first introduced and elevated in a retort and then fed laterally therefrom over grate bars. The present application constitutes a continuation in part of a pending application for patent, Serial No. 461,761, filed October 12, 1942.

With the type of stoker above referred to, it is customary to reciprocate certain of the grate bars to facilitate the feeding of the fuel downward thereover. It is also customary to provide means at the lower ends of said grate bars for disposing of the ash and in one construction this is accomplished by a rockable segmental member spaced from the side wall of the furnace. The rocking movement of this segmental member is generally accomplished by connecting the same to a reciprocatory grate bar so that the amplitude of reciprocatory movement of said grate bar determines the amplitude of rocking movement of the segmental member.

It is the object of the instant invention to obtain a construction in which the reciprocatory movement of the grate bars and the rocking movement of the segmental ash receiving member can be independently controlled. This is advantageous in securing complete combustion of the fuel on the grate bars and avoiding the disposal of any unconsumed fuel with the ash. Thus, under certain conditions it is desirable to leave the rocking segment stationary during the continued reciprocation of the grate bars. At other times it is desirable to oscillate the rocking members while the reciprocatory grate bars are stationary. Again it may be desirable to simultaneously move the reciprocating bars and the rocking members but with different degrees of movement. My invention, therefore, consists in the construction for accomplishing such operations as hereinafter set forth.

In the drawings:

Fig. 1 is a cross section through a stoker to which my improvements are applied;

Fig. 2 is a side elevation of the mechanism for actuating the movable members of the grate from the fuel feed mechanism;

Fig. 3 is a cross section on line 3—3, Fig. 2;

Fig. 4 is a cross section on line 4—4, Fig. 2;

Fig. 5 is a front elevation of the adjustable mechanism for rocking the segmental ash receiving members;

Fig. 6 is a cross section on line 6—6, Fig. 5; and

Fig. 7 is a horizontal section on line 7—7, Fig. 3.

As shown in Fig. 1, the retort A extends longitudinally in the center of the furnace and is pro-

vided with the usual feed (not shown) which advances and elevates the fuel therein. B and B' are grate bars extending laterally on opposite sides of the retort being supported at their inner ends on a flange A' of the retort and at their outer ends upon channel beams C and C'. The inner ends of these bars also constitute upper wall portions of the retort. The specific construction of these bars and the mechanism for reciprocating the same are fully described in the parent application for patent above referred to but will be only generally described in the present application. Thus, the grate bars in alignment with each other on opposite sides of the retort are connected to move together simultaneously in the same direction during each phase of the reciprocation. Rock shafts F and F' extending longitudinally on opposite sides of the retort are connected to actuate the bars, such connection comprising rock arms G and G' on the respective shafts, rods H extending beneath the retort and connecting said arms, and fingers G³ projecting upward from the arms and engaging recesses in the lower portions of the bars B and B'. Alternate groups of grate bars are reciprocated in opposite directions and are actuated respectively by the rock shafts G and G' which simultaneously rock in opposite directions. Thus, only one of the rock arms G and G' connected to each other by the rod H such, for instance, as the arm G is secured to its shaft, the other being free to rotate on its shaft. For actuating an adjacent grouping of grate bars, the arm G' is secured to the shaft F', the arm G being free to rotate on the shaft F.

At the outer and lower ends of the grate bars are segmental-rocker grate sections I and I' which receive the ash and feed it downward into pits therebeneath. The rocking of these segmental grates is effected by a mechanism which will be hereinafter described.

The mechanism for actuating the shafts F and F' is illustrated in Figs. 2 and 3 and is arranged in front of the furnace in which the stoker is located. Preferably it is operated by a reciprocatory ram L slidable within a housing L³ which ram is used for feeding the fuel into the retort and is movable perpendicular to the plane of Fig. 3 and to the right and left, Fig. 7. To this ram is connected by a cross shaft L' a member L² having internal helical grooves therein engaging corresponding helical flanges M of a rotary shaft M'. As shown, the shaft M' is journaled in a frame T forming a part of the stoker frame. The member L² includes a hub portion L⁴ engag-

ing the shaft L' , a body portion L^6 and a cap portion L^6 secured to each other by bolts L^7 , L^8 and L^9 . Thus, during the reciprocation of the ram the movement of the member L^2 therewith will impart a rotative movement to the shaft M' in one direction during the forward stroke and in the opposite direction during the return stroke. The shaft M' has at its inner end a flange M^2 to which is connected preferably through the medium of shear pins M^3 , a disc N , which in turn has a lost motion coupling connection with a head N' on one of the rocker shafts F , F' . A similar mechanism is arranged upon the opposite side of the ram, but with the helix thereof oppositely sloped, so that the rocking movement simultaneously imparted to the shafts F and F' is in opposite directions. The lost motion connection between the members N and N' is preferably formed by a lug N^2 on the latter, projecting between a pair of spaced lugs N^3 on the member N . There is also an adjustable screw N^4 engaging a correspondingly threaded bearing in the lug N^2 and projecting therefrom to bear against one of the lugs N^3 . When the screw is completely retracted, the free angular movement of the lug N^2 is equal to the full angular movement of the member N , so that no motion is communicated to the member N' . On the other hand, where the screw N^4 is fully projected, it will take up all of the lost motion, so that both members N and N' will have an equal amplitude of movement. It will, therefore, be understood that the angular movement of the shafts F and F' may be varied between zero and the full angular movement of the members M' and N .

For actuating the rocker grates I and I' , each of the members N is provided with a crank pin N^5 which engages a connecting rod O leading to a rock arm P on a polygonal rock shaft Q . On this rock shaft are sleeved upwardly extending rock arms Q' having rounded portions at their upper ends engaging segmental bearings Q^2 in the segmental rocker grates I and I' . These segmental rocker grates are connected at their lower ends to links R which extend at such an angle to the links Q' as to impart a substantially vertical movement to the outer ends of the grate during the substantially horizontal movement of the inner ends thereof. Tuyère members S projecting outward from the furnace wall S' extend in proximity to the outer ends of the rocker grates I , leaving only a comparatively narrow space therebetween through which the ash is discharged.

With the construction just described, the rocking movement of the member N is transmitted through the connecting rod O to the rock arm P which, by rocking the shaft Q , imparts a rocking or oscillatory movement to the grates I or I' . As the radial length of the rock arm P is substantially equal to that of the crank pin N^5 , the amplitude of angular movement of the grate will correspond to that on the members M' and N . I have, however, provided a lost motion connection by forming the rod O in two sections O' and O^2 , which have a telescopic engagement with each other. The outer section O' has slots O^3 in the opposite walls thereof, while the inner section is provided with a series of apertures O^4 with which a coupling pin O^5 is alternatively engaged. The arrangement is such that by changing the pin O^5 from one aperture to another, the amount of lost motion may be varied from zero to that equal

to the full movement of the member O' . This permits of imparting any desired amount of movement to the rocker grates I and I' up to the full angular movement of the member N , or, if desired, said rocker grates may be allowed to remain stationary. Thus, the amplitude of movement of the rockable grates may be varied with respect to the amplitude of the reciprocated grate members.

10 What I claim as my invention is:

1. In a stoker the combination with a retort and a reciprocatory ram for feeding fuel therein, of a rock shaft adjacent to said ram, a member connected to and movable with said ram having a helical engagement with said rock shaft to impart an oscillatory movement to the latter, and a grate member actuated by said rock shaft.

2. In a stoker the combination with a retort and a reciprocatory ram for feeding fuel therein, of a rock shaft adjacent to said ram, a member connected to and movable with said ram having a helical engagement with said rock shaft to impart an oscillatory movement to the latter, a grate bar extending laterally from said retort, a rock shaft for reciprocating said grate bar arranged in axial alignment with the aforesaid rock shaft and an adjustable lost motion connection between said rock shafts for varying the amplitude of reciprocatory movement of said grate bar.

3. In a stoker the combination with a retort, a reciprocatory grate bar extending laterally therefrom, an ash discharge member at the outer end of said reciprocatory grate bar and a reciprocatory ram for feeding fuel into said retort, of a shaft adjacent to said ram, a member connected and movable with said ram having a helical engagement with said shaft to impart an oscillatory movement thereto, a rock shaft for reciprocating said grate bar arranged in axial alignment with the aforesaid shaft, an adjustable lost motion connection between said shafts for varying the amplitude of movement of said grate bar, a crank connected to said first shaft, a rod connecting said crank with said ash discharge member to impart movement to the latter and a lost motion coupling in said rod adjustable to vary the movement imparted to the ash discharge member.

4. In a stoker the combination with a retort, grate bars extending laterally therefrom, a rockable ash discharge member at the outer ends of said grate bars and a reciprocatory ram for feeding fuel into said retort, of actuating mechanism for said grate bars and ash discharge member comprising a shaft arranged adjacent to said ram having a flange extending helically thereabout, a member connected to and movable with said ram embracing said shaft and having a helical groove for engaging said flange to impart an oscillatory movement to said shaft, a rock shaft beneath said grate bars having connection with certain of said bars to actuate the same, said rock shaft being in axial alignment with the aforesaid shaft, flanges secured to the adjacent ends of said shafts, a lug projecting from one of said flanges between a pair of lugs on the other flange forming a lost motion connection therebetween, and an adjustable screw engaging one of said lugs for varying the lost motion between the same and the operating lug whereby the amplitude of reciprocatory movement imparted to said grate bars may be varied.

ROYCE L. BEERS.
